INFANT'S FEEDING SPOON

Joseph P. McCarthy, Binghamton, N. Y.

Application November 1, 1949, Serial No. 5,816

Term of patent 14 years

(Cl. D44—29)

To all whom it may concern:

Be it known that I, Joseph P. McCarthy, a citizen of the United States of America, residing at Binghamton, in the county of Broome and State of New York, have invented a new, original, and ornamental Design for Infant's Feeding Spoon, of which the following is a specification, reference being had to the accompanying drawing, forming part hereof, in which:

Fig. 1 is a front elevational view of an infant's feeding spoon, showing my new design;

Fig. 2 is a side elevational view;

Fig. 3 is a rear elevational view;

Fig. 4 is a cross section on the line 4—4 of Fig. 1;

Fig. 5 is a cross section on the line 5—5 of Fig. 1; and

Fig. 6 is a cross section on the line 6—6 of Fig. 1.

I claim:

The ornamental design for an infant's feeding spoon, substantially as shown.

JOSEPH P. McCARTHY.
